UNITED STATES PATENT OFFICE.

ASBA B. FITCH, OF CHICAGO, ILLINOIS.

HOLDER FOR CONDUCTORS' CHECKS OR TICKETS.

1,060,072.

Specification of Letters Patent. Patented Apr. 29, 1913.

Application filed August 19, 1912. Serial No. 715,719.

To all whom it may concern:

Be it known that I, ASBA B. FITCH, a citizen of the United States, residing at Chicago, in the county of Cook and State of Illinois, have invented certain new and useful Improvements in Holders for Conductors' Checks or Tickets, of which the following is a specification.

This invention relates to certain new and useful improvements in a holder for tickets or checks, such as are used by railway conductors, to indicate that they have taken up examined, or punched, the regular railroad or passenger tickets of passengers, and to show to the conductor, at a glance, the destination of passengers, and it consists in certain peculiarities of the construction, novel arrangement, and operation of the various parts thereof, as will be hereinafter more fully set forth and specifically claimed.

The principal object of the invention, is, to provide holders of the above named general character, which shall be simple and inexpensive in construction, strong, durable, efficient in operation, and so made as to be especially adapted to be secured to the shades of car windows within view and easy reach of both conductor and passengers, yet so as not to interfere with the raising or lowering of the shades, or be concealed thereby when the shades are raised.

The invention also contemplates providing a single piece metallic holder that may be easily secured to a car-window shade, as above stated, or if desired, to the wall of the coach, and will have clamping portions between which the conductor may place one or more tickets or checks where they will be firmly held without danger of being jarred out by the vibration of the coach, or blown out by drafts, or otherwise accidentally dislocated.

Various other objects and advantages of the invention will be disclosed in the subjoined description and explanation.

In order to enable others skilled in the art to which the invention pertains to make and use the same I will now proceed to describe it referring to the accompanying drawing in which—

Figure 1, is a perspective view of a portion of the shade of the car-window showing my improved holder mounted thereon, and illustrating by dotted lines tickets held thereby in about the positions they will occupy when placed between the clamping

members of the holder by the conductor. Fig. 2, is a vertical sectional view taken on line 2—2, of Fig. 1, looking in the direction indicated by the arrows. Fig. 3, is a face view of a portion of the car-window shade showing the inner or supporting member of the holder secured thereto, but illustrating the front or spring member of the holder removed, and Fig. 4, is a face view of the blank out of which the holder is formed.

Like numerals of reference refer to corresponding parts throughout the different views of the drawing.

Referring now to Figs. 1 to 4 inclusive of the drawing, the reference numeral 10, designates a portion of a cloth shade for car-windows to the lower portion of which one or more of the holders may be attached at any suitable point on the shade, which shade may be mounted in the window frame in the usual or any well known way. The holder is made of a single piece of metal, of any suitable size and form, but by preference of substantially the shape shown in the drawing. This piece of metal is designated in Fig. 4, as a whole by the reference numeral 11, and is bent on a transverse line between its ends, as at 12, to form an inner or supporting member 13, and a spring or outer member 14, the upper or free end of which is provided with a lip 15, curved outwardly from the member 13, as is clearly shown in Figs. 1, and 2, of the drawing. While in its blank form the metal piece 11, is provided at about its middle with a transversely disposed slot 16, which is located in the lower portion of the member 13, of the holder. The plate 11, is also provided with pointed projections 17, and 18, which are stamped out of the plate 11, so that their pointed ends will be free to be turned at angles to the portions 14, and 13, of the holder on which said projections are formed, while their opposite ends will remain united to their respective portions 14, and 13. That portion of the holder which forms the member 13, when the plate 11, is bent on or about the line 12, so as to cause the member 14, to contact with or approximate the member 13, is formed on its surface adjacent to the member 14, with a series of projections 19, which are preferably arranged in transverse rows as shown in Fig. 4, and are produced by indenting the member 13, on its opposite surface. That portion of the plate or blank 11, forming the member 14, is pro-

105

110

vided on its surface adjacent to the member 13, with a series of projections 20, which are also produced by indentations on the opposite side of the member 14. The projections 20, are arranged, a portion in a transverse line and part in a curved line and in such a manner that when the piece 11, is bent on the line 12, or thereabout the transverse line of projections 20, will lie along the lower transverse line of the projections 19, on the part 13, while some of the projections 20, of the curved line will be located a slight distance below and some above the upper line of the projections 19, as will be readily understood by reference to Fig. 3, of the drawing, in which the position of the projections 20, are indicated by dotted lines while the projections 19, are shown in full lines. From this view it will be seen that the projections 20, of the transverse line are alternately disposed with respect to the projections 19, in the lower line thereof, and that the projections 20, of the curved line are arranged in staggered relation with respect to the projections 19, in the upper line thereof. By this arrangement of the projections 19, and 20, on the opposing surfaces of the members 13, and 14, it is apparent that when the tickets or checks 21, are placed between the members 13, and 14, they will be firmly held in position by reason of the said projections, and that as the projections on one of said members are located between or in staggered relation with the projections on the other member, the tickets or checks will be depressed at such points, on account of the flexible material of the tickets, so that they will be securely held and in such a manner that they will not be torn or disfigured when withdrawn from the holder.

It will be understood that after the blank 11, shown in Fig. 4, has been formed as above described, the projection 17, on the member 14, is extended from said member 45 at substantially a right angle when its pointed end will be adapted to pass through the slot 16, of the member 13, and that the projection 18, will be extended rearwardly therefrom at an angle, so that said projection 50 may be forced through the shade cloth 10, and bent upwardly thereon as is clearly shown in Fig. 2, of the drawing, in which figure it will be seen that the pointed end 18^a, of the projection 18, is inwardly de-

flected and that the pointed end 17^a, of the projection 17, is likewise deflected, which, when said projections are pressed toward their respective members 14, and 13, will rest against the rear surfaces of the member 13.

To prevent the possibility of the holder being torn off of the shade 10, a reinforcing strip or sheet 22, is placed on the outer surface of said shade and will be pierced by the projections 17, and 18, of the holder 65 as is apparent by reference to Fig. 2, of the drawing.

By providing the members 13, and 14, with projections on their adjacent surfaces, it is obvious that two tickets can be inserted 70 between said members from opposite sides, as shown in Fig. 1, of the drawings, and that either one can be withdrawn without disturbing the other ticket, for the projections will provide a more positive gripping 75 or holding means than if they were not employed.

Having thus fully described my invention what I claim as new and desire to secure by Letters Patent is—

A holder for tickets and the like consisting of a single piece of material bent back upon itself to form clamping members, one of said members having near its free end and integral therewith a pointed projection 85 extended from its surface in a direction opposite the other clamping member and having near its other end a slot, the other clamping member being slightly resilient and having a pointed projection integral therewith 90 and extended therefrom and through said slot of the first named clamping member, one of said members having on its inner surface a series of projections arranged in transverse rows and the other of said members having on its inner surface a series of 95 projections arranged in a transverse and a circular row, the projections of the last named transverse row arranged in staggered relation with one of the first named transverse rows of projections and the curved row 100 of projections arranged in staggered relation with the other of said rows.

ASBA B. FITCH.
